WINDING MACHINE

Andrew S. Gill, Jr., Maple Heights, Ohio, assignor
to Eaton Manufacturing Company, Cleveland,
Ohio, a corporation of Ohio

Application March 24, 1951, Serial No. 217,327

19 Claims. (Cl. 242—45)

1

This invention relates to winding machines and more particularly to improvements in said machines and in the control mechanism therefor.

Broadly the invention comprehends the provision of machines for winding thread, yarn and the like from skeins onto spools having control mechanism associated therewith effective to automatically cause a nibbling action upon the material being wound when the material becomes excessively tensioned due to snags, tangles or the like interfering with its normally free movement between the skein and spool in the winding thereof onto the spool to eliminate said snags or the like in most instances without requiring complete cessation of the winding operation. The control mechanism includes electromagnetically operated and controlled brake and clutch devices and an electrical circuit therefor having a switch as a part thereof which is actuated when the material being wound exceeds a predetermined established winding tension to initiate operation of the electrical circuit.

Although numerous winding machines have been devised, manufactured and used none have prior to the present development provided mechanism which will operate to eliminate tangles or other like interferences of a specific nature occurring in the material in the course of its winding operation without requiring the complete cessation of the winding operation and without damage resulting to the material being wound. The present mechanism is further adapted to effect a complete cessation of the winding operation if the interference encountered is of a certain magnitude which requires manual handling.

Among the several objects of the invention is the provision of a winding machine having electromagnetically operated brake and clutch devices incorporated therein controlled as by an electrical circuit actuated by the tension of the material being wound that is effective to eliminate a great majority of tangles or like interference occurring at the skein in the winding of the material upon a spool therefrom without necessitating the complete cessation of the winding operation; that will eliminate said tangles without causing damage to or breakage of the material; and that will operate to effect cessation of the winding operation when the tangles or other interferences are of such a nature that cannot be eliminated without requirement for manual handling thereof; that operates upon the energization of the electrical circuit to effect an alternate braking and clutching operation whereby the material is nibbled or wound upon the

2

spool at a slow pulsing rate until either the tangle is eliminated or the winding operation is completely stopped.

Other objects and advantages of the invention will appear from the following description taken in connection with the drawings forming a part of the specification; and in which:

Fig. 1 is a front elevation view of a winding machine constituting the basis of the invention;

10 Fig. 2 is an end view of the winding machine taken substantially along lines 2—2 of Fig. 1;

Fig. 3 is an end view of the winding machine taken substantially along lines 3—3 of Fig. 1;

15 Fig. 4 is an enlarged fragmentary front elevation and partially cross-sectionalized view of the brake and clutch device incorporated in the machine of Fig. 1;

Fig. 5 is a schematic illustration of the electrical control circuit for the winding machine;

20 Fig. 6 is an oscillograph test curve illustrating a normal winding operation of the machine of Fig. 1;

Fig. 7 is another oscillograph test curve illustrating a winding operation of the machine of Fig. 1 when a nibbling operation thereof is encountered;

25 Fig. 8 is a modified form of material tensioning mechanism from that employed in the machine of Fig. 2;

30 Fig. 9 is a modified form of electrical control circuit for the winding machine as employing the tensioning mechanism of Fig. 8; and

Fig. 10 is a modified form of clutch and brake device of Fig. 4.

35 Similar reference characters indicate corresponding parts throughout the several views of the drawings.

The present winding machine and control mechanism therefor was devised for the purpose 40 of accomplishing a result in the art of winding material such as yarn, thread and the like upon a spool as it is removed from a skein whereby said winding can progress continuously although tangles normally occurring in the removal of the material from the skein are present, tending toward injury to or breakage of the material, said result of which has never heretofore been done. The tangles occurring in the material which usually occur at the skein acting to overstress the material resulting in either damage to or breakage of the material if they are not eliminated or the winding operation stopped are herein eliminated in most instances, if not too severe, without necessity of completely stopping the winding operation by a progressive nibbling or

tugging action being imposed upon the material at the spool through a controlled alternate rotation and braking of the rotation thereof, said rotation being of predetermined small increments. By so tugging at the material being wound whenever a tangle occurs acting to tension the material beyond a predetermined amount the tangle is eliminated and the material is once again permitted to assume its normal movement between the skein and spool.

As a means of effecting a nibbling or tugging of the material being wound associated electro-magnetically operated brake and clutch devices are incorporated in the machine such that the clutch is normally engaged when a winding operation is desired effective to transmit power therethrough from a driving source to rotate the spool of the machine and cause a winding of material therein as it is simultaneously removed from a skein. The brake device on the other hand is operative substantially simultaneously with the disengagement of the clutch device to effect a sudden stopping of rotation of the spool. The brake and clutch devices each have their coils arranged in an electrical control circuit therefor, said circuit having a switch therein which is tripped to close the circuit and initiate the operation thereof when the material being wound upon the spool exceeds a certain predetermined tension. The tension permitted on the material varies with the type of material being wound but is so established in any case that the permitting of a much greater tension would result in damage to the material even though it would not be great enough to cause the breakage thereof. The electrical circuit for the brake and clutch devices includes heat actuated switches and relays operative upon energization of the circuit to establish a predetermined timed cycle of alternate operation of the brake and clutch devices so that a nibbling action is imposed on the material being wound. If the nibbling operation succeeds in undoing the tangle in the material which caused the tensioning thereof sufficient to trip the switch of the circuit to place said circuit in operation, said switch will again automatically be opened and the normal winding operation of the machine will be resumed at least until another tangle or the like is encountered. When a tangle of a serious nature is encountered the nibbling operation will continue for a predetermined time as established by the presetting of one of the heat actuated switches in the circuit; whereupon if the tangle is not removed the main electrical circuit for the operation of the machine is opened and the winding operation is completely stopped. The winding operation thereafter cannot be resumed until the switch of the main circuit is manually reset, thereby informing one operating the machine that the tangle must be manually removed before the machine should be again placed in operation. As an alternative to the use of the last mentioned heat actuated switch a trip switch can be employed engageable upon the excessive tensioning of the material to immediately engage the brake of the machine effective to instantaneously retard rotation of the spool and thus prevent further winding until the cause is eliminated.

Referring to the drawings for more specific details of the invention 19 represents generally a winding machine comprising basically a main frame 12, a rotating spindle 14, rotatable cam mechanism 16 and a clutch and brake mechanism 18.

The spindle 14 is journaled in the frame at spaced points and has a combination brake and clutch plate 20 splined near one end 22 thereon, the purpose of which will hereinafter appear, a pulley 24 fixedly secured on end 22 thereof, the purpose of which will hereinafter appear and a spool 26 mounted upon its opposite axial end from end 22.

The cam mechanism 16 includes a cylinder 28, having a cam slot 30 in its peripheral surface, including a shaft 32 fixedly secured thereto journaled in the frame 12 and a traverse bar 34 including a pin 36 engageable in the cam slot 30.

The shaft 32 of cylinder 28 is driven by way of a gear mechanism, not shown, enclosed in gear box 38 from a belt 40 having driving connection between pulley 24 and a pulley 42 associated with the gear mechanism in gear box 38. The gear mechanism provides for the proper related speed of the cam mechanism to that of the spindle.

The traverse bar 34 is supported for axial movement upon a rod 36 forming part of main frame 12 and includes a guide 44 for the material to be wound upon the spool 26, said guide being adapted to bear lightly upon the outer periphery of the material as it is wound upon the spool.

The clutch and brake mechanism includes in addition to the clutch and brake plate 20 a driven input clutch member 46 which together with the plate 20 constitutes a magnetic clutch device 48 and a stationary brake member 50 which together with the plate 20 constitutes a magnetic brake device 52, said member 50 being rigidly secured upon frame 12 and journaled in relation to spindle 14 intermediate the plate 20 and pulley 24 whereas the clutch member 46 is journaled on spindle 14 by way of bearings 54 mounted on the spindle.

Clutch member 46 has a pulley 56 formed therein and provides a U-shaped cross-sectional portion having an annular electromagnetic coil 57 mounted in nested relation between the arms of the U-shaped portions, said coil being supplied current by way of current conducting brush 58 having current conducting engagement upon a conductor ring 60 having connection with one end of the coil.

The brake member 50 similarly to clutch member 46 is U-shaped in cross-section and has an electromagnetic coil 62 mounted in nested relation therein, said coil being supplied current by way of electrical connection therewith.

The clutch and brake members 46 and 50 are axially spaced with respect to one another with their respective pole faces 64 and 66 facing one another for engagement alternately with annular friction linings 68 and 70 secured upon opposite faces of the plate 20. The plate 20 dependent upon which coil is energized is magnetically drawn into frictional engagement with one or the other of the clutch and brake members, such that upon engagement with clutch member 46 and wherein the clutch member is being driven from a power source, not shown, by way of belt 70 connected thereto, rotation is imparted to the spindle to effect a winding of the material upon the cone spool 26 mounted thereon. Simultaneously with rotation of the spindle the belt 48 connected between pulleys 24 and 42 drives cam mechanism cylinder 28 by way of gear box 38. When the coil 57 of the clutch device 48 is deenergized and the coil 62 of the brake is energized, the plate 20 is immediately released

from frictional engagement with clutch member 46 and by way of friction linings 70 is frictionally engaged upon the pole faces of the brake member 50 thereby effecting a quick and smooth braking of the spindle and the winding operation. The linings 68 and 70 are preferably of the low magnetic reluctance type such as defined in A. Winther application Ser. No. 91,792 although any suitable lining which does not appreciably block the flow of magnetic lines of flux there-through can be used.

The material 72 to be wound upon the cone spool 26 in passing from the skein to the spool is threaded through a tension gate 74 suitably mounted upon the main frame, passed through a loop guide 76, over a guide rod 78, over a guide in the form of a rotatable pulley 80, looped over a rotatable guide pulley 82 forming part of a material tensioning mechanism 84, through a loop guide 86 and thence through thread guide 44 20 onto the cone spool.

The rotatable guide pulley 80 is mounted upon a pivotal lever arrangement 88, pulley 80 being mounted at the extremity of arm 90 thereof whereas another arm 92 thereof engages a micro trip switch 94 forming part of electrical system 96 utilized in controlling the operation of the machine.

The electrical system 96 includes a power source 98 in the form of an A. C. current supply and a rectifier 100 providing D. C. power for the circuit, the switch 94 which is herein designated a tension limit switch, a quick acting heat actuated switch 102, a heat actuated switch with manual reset 104, relays 106 and 108, rheostats 110, 112 and 114 and the clutch and brake coils 57 and 62 respectively.

Relay 106 is a two circuit arrangement including one set of single pole, double throw contacts 116 said contacts being designated 118, 120 and 122 and one set of single pole, single throw normally closed contacts 124 whereas relay 108 is a two circuit arrangement including one set of single pole, double throw contacts 126, said contacts being designated 128, 130 and 132 and one set of single pole single throw normally closed contacts 134.

The quick acting heat actuated switch 102 can be in the form of a bi-metal with an electrical heater which operates a snap action switch thereof and can be pre-set for say two to five seconds operation, depending upon the kind of material being wound and the winding operation desired, to begin a nibbling operation of the machine when the switch is initially closed.

Heat actuated switch with manual reset 104 like heat actuated switch 102 can be in the form of a bi-metal with an electrical heater which operates a snap action switch thereof, effective upon the opening of the switch to open the main feed circuit to the coils 57 and 62 of the respective clutch and brake devices and thus cease winding operation of the machine. The electrical heater of the heat actuated switch 104 per se is normally pre-set between thirty and sixty seconds before it operates to open the snap switch thereof.

Rheostat 110 is used to regulate the voltage to the clutch coil 57 during normal operation thereof so that a very soft, smooth operation can be obtained and no undue strain is placed upon the material being wound upon the spool. Rheostat 112 controls the rate at which relay 108 will go through its cycle thus permitting changes thereof as may be deemed necessary. The desirable

elapsed operating time of heat actuated switch 102 can be varied by rheostat 114 arranged in the feed line therefor and a rheostat similar thereto may be employed relative to heat actuated switch 104 if it is so deemed necessary.

In a normal operation of winding machine 10 assuming power is being delivered to clutch member 46 by way of pulley belt 70 attached thereto and that electrical power is being supplied through the electrical system by way of feed line 136 to the clutch coil 57, a rotation of the spindle is obtained such that with material being supplied to the spool mounted thereon a winding operation is commenced. With the rotation of the spool 26 the material guide 44 bearing upon the spool is shuttled back and forth across the width of the spool, through the action of traverse bar 34 being controlled in movement by way of its engagement with the cam slotted cylinder 28 to properly place the material upon the spool in predetermined desired orderly manner. This winding operation continues so long as no undue tension of a preestablished amount is imposed on the material. During the normal course of the winding operation such as wherein the material is first wound in a small diametered portion of the spool and progressively upon a larger diametered portion thereof and reversely when the traverse bar is reversed in direction of axial movement the tensioning mechanism operates by way of imposing a predetermined initial load upon the material to reduce the size of the loop of the material without causing damage to the material or interfering with the smooth flow of material in the course of its being wound upon the spool. The rotatable guide pulley 82 forming a part of the tensioning mechanism in being moved to reduce the size of the loop arranged thereover operates against the resistance of tension spring 138 and thus increases the tension imposed on the material. This tensioning is so controlled that when a predetermined established tension on the material is exceeded it acts through lever 88 moved about its pivot through the engagement of the material upon pulley 80 to trip switch 94 and thus place the nibbling control of electrical system 96 into operation. This excessive tension being imposed on the material usually occurs as a result of tangles which are present in the skein from which the material is being unwound and it is the concern here to remove these tangles if possible without causing damage to or breakage of the material and without completely stopping the winding operation of the machine.

With switch 94 in closed position, circuit 140 is completed by way of contact points 120 and 122 of switch 116 through heater element 142 of switch 102, rheostat 114 and switch 124 to ground. A circuit 144 parallel to circuit 140 is completed by way of rheostat 112 and coil 146 of relay 108 to the ground and another parallel circuit 148 is completed by way of heater element 150 of switch 104 to ground.

By so energizing coil 146, switch 126 is initially tripped by the clapper, of the relay 108, not shown, thus breaking circuit 136 to the clutch device by moving contact 130 out of engagement with contact 128 thus causing deenergization of the coil 57 thereof and simultaneously closing the circuit to the brake device by moving contact 130 into engagement with contact 132 to thus energize the coil 62 of the brake device and effect a movement of plate 20 into engagement with brake member 50 for a braking of the spindle.

thereby. As the clapper of relay 108 is moved further in its operative path, switch 134 is moved to break circuit 152 in which it is arranged.

Simultaneously with the energization of coil 146 and operation of switches 126 and 134 associated therewith, the heater element in accordance with its pre-established setting of say two to five seconds closes circuit 154 after said time by way of contacts 156 and 158 becoming engaged which acts through coil 160 to its ground to energize same, whereupon coil 160 acts to trip switches 116 and 124 of its relay.

As switch 116 is tripped contact 120 thereof engages contact 118 to complete the circuit common thereto maintaining the coil 160 energized whereas the breaking of engagement between contacts 120 and 122 disrupts the circuit to heater element 142 and circuit 144 to coil 146 of relay 108. Contacts 162 and 164 of switch 124 are moved apart by the action of coil 160 thereby further assuring the disruption of operation of the heater element.

Upon coil 146 of relay 108 being de-energized, the switches 126 and 134 are consecutively tripped reversely to their operation when coil 146 was energized such that the contacts 128 and 130 of switch 126 are engaged effective to close circuit 136 to once again energize the coil 57 of the clutch device to provide for the operation thereof while simultaneously the contacts 130 and 132 of switch 126 are moved apart to open circuit 152 to coil 62 of the brake device thereby releasing the braking action upon the spindle. With switch 134 moved by action of coil 146 to close the circuit in which it is in series with current is supplied therethrough to the coil 146 of relay 108 for the energization thereof to once again trip switches 126 and 134 associated therewith and cause a flow of current to the brake coil 62 and open the circuit to coil 57 of the clutch device thereby effecting a braking action upon the spindle as the clutch is released. This cycling on and off action of the coil 146 of relay 108 by virtue of switch 126 being tripped in one direction to simultaneously close the circuit to the coil 57 and open the circuit to the coil 62 and in the other direction to open the circuit to the coil 57 and close the circuit to the coil 62 affords an alternate on and off clutching and braking action upon the spindle such that a nibbling action is effected in the attempt to remove the tangles or whatever other interference has operated to tension the material being wound an amount sufficient to trip tension switch 94. The nibbling or on and off clutching and braking action upon the spindle will either continue for a time until said interference is removed permitting of the release of load upon tension switch 94 so that circuit therethrough is broken and a positive clutching action is had through feed line 136 to the clutch coil 57 by way of contacts 128 and 130 of switch 126. At the time of switch 94 being tripped to open position the nibbling circuits of the electrical system are cut off from the current source and assume their positions of rest as disclosed by Fig. 5.

Should the off and on cycling action of the relay 108 continue up to the preestablished setting time of heater element 150 of switch 104 the contacts 166 and 168 of the switch will be moved apart to thus totally disrupt the electrical system and cause a complete cessation of winding operation. With this result the tangles or whatever other interference of effecting a smooth winding operation which can not be accounted

for by the nibbling operation will have to be manually or otherwise removed before switch 104 can be manually reset to once again place the machine in operation.

It will be noted in the above recitation of the completion of the circuit to the heating element 142 of switch 102 that during this stage of operation the brake will be maintained engaged the preestablished setting time of the heater element 142 before the nibbling operation is set into action upon the contacts 156 and 158 of switch 102 coming into engagement to energize coil 160 of relay 106 which in turn brings about the cycling action of relay 108. By so holding the brake engaged before the nibbling action is placed in motion a smooth nibbling action is assured without causing damage to the material as might otherwise occur if the interference encountered would suddenly be released and immediately another interference would be encountered. Once the contacts 156 and 158 have been engaged through the action of heating element 142 effective to close the circuit to the coil 160 of relay 106 they serve no further purpose especially since upon the circuit to the heating element being open when the energized coil 160 operates to move the contacts 120 and 122 apart to their normal open position and will not assume a further function until an entirely new nibbling operation is to be started at a subsequent time in the winding operation.

Coil 160 in being energized operating to move contacts 162 and 164 apart positively assures a breaking of any and all circuits through the heating element 142 to the ground so that once the heating element 142 has been supplied current for its closing of switch 102 no more current can be supplied thereto until a new nibbling operation is begun.

Curves A and B shown by the respective Fig. 6 and 7 illustrate actual oscillograph test curves obtained in the operation of the winding machine of Fig. 1 incorporating the controls of Fig. 5. Curve A represents a normal operating condition of the machine wherein the peaks and dwells of the curve define the variations in tension acting upon the material being wound, said variations for this particular test being in the neighborhood of 25 grams with tension peaks of about 30 grams, an amount permissibly established at which the winding operation can continue without need for retardation of any degree being imposed for the damage free winding of the material.

Curve B on the other hand represents a condition wherein the nibbling operation comes into effect whereby a continuing tension in the amount of about 40 grams being imposed upon the material, acting through switch 94 to trip same the electrical circuits are set into operation for the cycling action of the clutch and brake devices into operation. The condition will prevail as noted for such time as the interference remains whereupon once it is removed the normal operation is resumed as indicated by curve A of Fig. 6. These curves very clearly disclose the comparison of operation when the machine is functioning normally and when undue and excessive tension is imposed upon the material being wound and also that the nibbling operation is a reasonably constant condition safeguarding any damage to or breakage of the material.

Fig. 8 discloses a modified form of material tensioning mechanism 166 from that mechanism 84 disclosed in Fig. 2 which is equally adaptable to machine 10.

The mechanism 166 basically includes a pivotal lever 168 having oppositely disposed arms 170 and 172, arm 170, being greater in length than arm 172, having a guide pulley 174 at the extremity thereof upon which, the material to be wound on the spool of the machine passes in the course of its movement from the tension gate 74 to spool 26. Arm 172 has a spring 176 connected to the end thereof effective to exert a tension upon the material passing over pulley 174 of arm 170 so as to normally maintain the arm 170 in engagement with a switch 178.

The material to be wound on the spool in addition to passing over pulley 174 passes over guide pulleys 180 and 182, arranged respectively before and after the guide pulley 174, and a guide bar 184 arranged near the spool.

A movement limiting element 186 resists movement of arm 170 in one direction opposing the tension of spring 176 to a position where the arm engages switch 94.

A trip switch 188 is engageable by arm 172 upon movement of arm 170 as induced by a tension pull of the material upon pulley 174 thereof operating to take up the material extending over pulley 174 between pulleys 180 and 182.

Switch 178 is for all purposes similar to switch 94 for it is operated likewise in the place thereof the only difference being that switch 94 is moved to close circuit 140 whereas switch 178 is released to close circuit 140.

Whereas switch 178 is substituted in the control system of Fig. 5 for switch 94, the switch 188 eliminates the necessity of heater switch with manual reset 104 such that instead of providing a heater controlled switch as a means of shutting off complete operation of the winding machine switch 188 operates to immediately cause engagement of the brake and thus afford instantaneous retardation of movement of the spool. Fig. 9 schematically illustrates the circuit in which switches 178 and 188 common to mechanism 166 are employed. As noted switch 188 in being introduced into the electrical system of Fig. 5 replaces the heater switch 104 whereby in one position of operation it forms a part of the circuit for the nibbling operation of the winding machine and in its position as tripped by the arm 172 closes the circuit directly to the coil 62 of the brake device for the operation thereof.

The lever 168 in its initial movement as caused by more than normal tension on the material being wound, operates likewise as the lever 86 of Fig. 2 to effect a closing of circuit 140 through switch 178 for establishing a nibbling operation cycle of the electrical control system. If the interference to the movement of the material continues such that the material passed over pulley 174 between pulleys 180 and 182 is taken up resulting in the movement of arm 170 and consequently also arm 172 attached thereto to a position causing engagement of switch 188 by arm 172, the switch 188 is tripped to position to close the circuit to energize coil 62 of brake 50 for its immediate application. In so positively applying brake 50 rather than merely disrupting the electrical control system, a positive and immediate cessation of rotation of the spool is accomplished thereby insuring against any possible drifting action of the spool which might be sufficient to destroy the material being wound.

Fig. 10 discloses a modified form of brake and clutch device 190 from that shown by Fig. 4 the major difference being the provision of an eddy current clutch 192 in substitution for the clutch 46 whereby as it may be desired the speed of the spool by way of shaft 14 can be operated at a desired regulated speed providing for the constant linear speed of the material as it varies in its being wound upon the smaller and larger 10 diameter portions of the spool and also as the amount of material tends to increase in overall diameter as wound upon the spool.

The device 190, includes clutch 192 consisting of a pulley driven coil supporting rotor 194 and a drum member 196 fixedly secured through a hub 198 thereof to the shaft 14 and a brake consisting of a coil supporting stator 200 and a braking plate 202 formed as part of drum member 196 having a brake lining 204 thereon. The stator is resiliently axially secured to an abutment 206 and is axially relatively movable thereto for engagement of friction surfaces thereof upon the lining 204.

The operational control of the brake and clutch device 190 can be accomplished as applied to the winding machine of Fig. 1 in a like manner to the mechanism 18 merely by the substitution of the respective coils of the brake and clutch thereof in the electrical control systems of either Fig. 5 or 9.

The clutch 192 is believed to be amply representative in its disclosure as being of the conventionally used eddy current type which is slip controllable by rheostatic means or the like, 35 not shown, and therefore it is not felt that the detailed structure thereof need be further defined.

Although this invention has been disclosed specifically as relates to the type of winding 40 machine used and the constructional components thereof and employs a specific electrical system for the control thereof, they are to be recognized merely as illustrative of the basic ideas and fundamentals embodied therein such 45 that the invention is to be construed in the light of the claims appended hereto.

What I claim is:

1. In a winding machine, a winding spindle, a clutch, engageable with the spindle, having a magnetic coil, a brake, engageable with the spindle, having a magnetic coil, power means for driving the clutch, and a current supplied electrical control system including the brake and clutch coils, rapid continuous cycling means 50 for alternately energizing and de-energizing the brake and clutch coils, switch means controlled by the tension of a strand of material being wound upon the spindle effective to be closed upon a predetermined tension of the strand of material, for placing the brake and clutch coil alternately energizing and de-energizing means in operation, and means for deenergizing the clutch coil and for simultaneously energizing the brake coil effective to inhibit rotation of the spindle after a predetermined time of operation of the alternately energizing and deenergizing means and with the switch closed.

2. A winding machine according to claim 1 70 wherein a heater switch is included in the electrical control system to control the flow of current therein.

3. A winding machine according to claim 1 wherein a heater switch is included in the means 75 for alternately energizing and de-energizing the

11

brake and clutch coils operative to delay the initial alternating cycle thereof.

4. A winding machine according to claim 1 wherein a tensioning mechanism engages the material being wound for limiting the tension imposed on the material prior to the operation of the switch means controlled by the material.

5. A winding machine according to claim 1 wherein the electrical control system includes two relays, one of which is operative to set the other relay into cycling operation.

6. A winding machine according to claim 5 wherein each relay includes two circuits, one circuit of each having one set of single pole, single throw normally closed contacts and the other circuit of each having one set of single pole, double throw contacts.

7. A winding machine according to claim 1 wherein the clutch coil has a rheostat therefor.

8. A winding machine according to claim 6 wherein each relay includes a coil operative upon the energization thereof to reverse the position of the contacts of the switches thereof.

9. A winding machine according to claim 1 wherein the clutch is a slip controllable eddy current type clutch.

10. A winding machine according to claim 1 wherein the clutch and brake are of the friction plate type.

11. A winding machine according to claim 1 wherein a tensioning mechanism, over which the material to be wound on the spindle passes, includes a movable element engageable with the switch means.

12. A winding machine according to claim 11 wherein the electrical control system includes a circuit supplying current directly to the brake coil and a second switch positionable to supply current either to the means for alternately energizing and de-energizing or to the brake coil circuit.

13. A winding machine according to claim 12 wherein the movable element of the tensioning mechanism is a two armed lever, one arm of which engages the material to be wound and the other arm of which engages the second switch means.

14. A winding machine according to claim 13 wherein the one arm engageable with the second switch means is spring tensioned in an opposite direction to the pull of the material engaging the other arm.

15. A winding machine according to claim 14 wherein the arm engageable with the second switch means is comparatively much shorter than the other arm of the lever and the longer arm is engageable with the first mentioned switch means.

16. In a winding machine, a winding spindle, a clutch, engageable with the spindle, having a magnetic coil, a brake, engageable with the spindle, having a magnetic coil, power means for driving the clutch, and a current supplied electrical control system including the brake and clutch coils, means for alternately energizing and de-energizing the brake and clutch coils, a heater switch in the means for alternately energizing and de-energizing the brake and clutch coils operative to delay the initial alternating cycle thereof, a heater switch in the electrical control system, apart from the brake and clutch coil alternating energizing and de-energizing means, operative to control the flow of current through the system, and switch means con-

12

trolled by the tension of a strand of material being wound upon the spindle for placing the brake and clutch coil alternately energizing and de-energizing means in operation.

5 17. A winding machine according to claim 16 wherein the heater switches each include a pair of contacts and a heater element and wherein the heater switch included in the alternating means has a rheostat control for the heater element thereof.

10 18. In a winding machine, a winding spindle, a clutch, engageable with the spindle, having a magnetic coil, a brake, engageable with the spindle, having a magnetic coil, power means for driving the clutch, and a current supplied electrical control system including the brake and clutch coils, means for alternately energizing and de-energizing the brake and clutch coils, a circuit supplying current directly to the brake coil independent of the means for alternately energizing and de-energizing the brake and clutch coils, a heater switch included in the means for alternately energizing and de-energizing the brake and clutch coils operative to delay the initial alternating cycle thereof, switch means controlled by the tension of a strand of material being wound upon the spindle for placing the brake and clutch coil alternately energizing and de-energizing means in operation, and a switch in the control system positionable to supply current either directly to the brake coil circuit or to the alternately energizing and de-energizing means, said last mentioned switch being controlled by the strand of material to be wound upon the spindle.

15 19. In a winding machine, a winding spindle, a clutch, engageable with the spindle, having a magnetic coil, a brake, engageable with the spindle, having a magnetic coil, power means for driving the clutch, and a current supplied electrical control system including the brake and clutch coils, rapid continuous cycling means for alternately energizing and de-energizing the brake and clutch coils and switch means controlled by the tension of a strand of material being wound upon the spindle for placing the brake and clutch coil alternately energizing and de-energizing means in operation, said alternately energizing and de-energizing means including relay mechanism operative upon actuation of the switch means to establish a continuous cycling operation of said energizing and deenergizing means for a predetermined tension of the strand of material for a predetermined time and to discontinue operation of the machine when said predetermined tension is continued for a period of time in excess of the predetermined timed operation of the energizing and deenergizing means.
